UNITED STATES PATENT OFFICE.

WILLIAM J. KEHOE, OF WASHINGTON, DISTRICT OF COLUMBIA.

STENOGRAPHIC MACHINE.

940,255.

Specification of Letters Patent. Patented Nov. 16, 1909.

Application filed March 25, 1909. Serial No. 485,719.

To all whom it may concern:

Be it known that I, WILLIAM J. KEHOE, a citizen of the United States, residing in Washington, District of Columbia, have invented certain new and useful Improvements in Stenographic Machines, of which the following is a specification.

My present invention relates to stenographic machines of the kind shown in Letters Patent of the United States No. 865,910 granted to me Sept. 10, 1907, and in my Patent No. 908,575, of Jan. 5, 1909, and the primary object of my invention is to so improve machines of this kind that they may be operated noiselessly and with absolute precision, in the feed of the paper and the printing of the characters. I have also improved the details of construction of the machine in the manner hereinafter explained.

In the accompanying drawings, Figure 1 is a plan view of a stenographic machine embodying my improvements, part of the paper reel being omitted. Fig. 2 shows a longitudinal central section on the line 2—2 of Fig. 1. Fig. 3 shows a transverse section on the line 3—3 of Fig. 1. Fig. 4 is a view on an enlarged scale showing particularly the ratchet and detent mechanism. Figs. 5, 6 and 7 are detail views of the pawl forming part of the ratchet mechanism. Fig. 8 shows a rear elevation of the machine, a part of the paper reel being broken away. Fig. 9 is a detail view, showing particularly one of the paper guides employed. Fig. 10 is a plan view of the keys and some parts associated therewith, showing particularly the arrangement of the bearing bars on which the keys rock and the relation of the bearings with the type and with those parts of the keys which engage the feed plate of the machine. Fig. 11 shows a transverse section on the line 11—11 of Fig. 10. Fig. 12 shows a vertical central section on the line 12—12 of Fig. 11. Fig. 13 is a perspective view of one of the key levers and the bearing bar to which it is attached. Fig. 14 is a detail view in section, and on an enlarged scale, showing how the bearing bar of each key lever is supported. Fig. 15 is a detail view in perspective showing one of the spacing blocks, which is interposed between each key lever and its bearing bar.

The base or bed plate comprises a back part A, sides A¹, A¹, and a front part A²,

the center or middle part being cut away. This bed plate may be made of sheet metal flanged as shown at a to strengthen it, and it may be supported on feet a' of soft material, as usual. To the back part A of the base plate is secured a bracket B to opposite ends of which are attached the stud shafts c, carrying the spools C of the ribbon Y. Each ribbon spool C is connected with a vertically-arranged spur-wheel C¹ which is adapted to be driven by a train of gears carried by a lever D pivoted to the bracket B at b, mid-way between its opposite ends. The outermost spur-wheel d is in permanent mesh with an intermediate spur-wheel d¹ which meshes with a pinion d² on the feed shaft E which revolves about an axis in line with the axis of the pivot about which the lever D turns. This lever is formed with a downwardly-projecting arm d³ which bears against a spring bar F resting at opposite ends on the stud shafts c and it has mid-way between its ends a depression d⁴ directly under the pivoted point of the lever D.

The arm d³ is adapted to butt against either of the stop pins d⁵ on opposite sides of the pivot b; the arrangement being such that when the lever is thrown over to either side to bring the spur-wheel d into engagement with either of the spur wheels C¹ the lever will be held by the spring F against one of the stops d⁵ while the spur-wheel d is held in engagement with the wheel C¹. In this way while the gearing is properly effected undue pressure or friction between the gears d and C¹ is prevented and thus the ease with which the machine is operated is materially increased.

The lever D with the gears d, d¹ may be held in an inoperative position so as to disconnect the gears d, C¹ by bringing the arm d³ into engagement with the depressed portion d⁴ of the bar F.

The paper ribbon X is drawn from a reel G by supported levers G¹ pivoted to the bracket G² mounted on the left-hand side of the machine and the paper passes through a guide loop g, carried by an arm g¹ attached to a bracket g² which also carries a spring plate h in the lower bifurcated end of the downwardly-projecting portion of which is mounted a feed roller H preferably made of relatively soft material, such as rubber. The position of the guide g may be regulated by the adjusting devices g³ and the

position of the feed roller H may be adjusted by means of the set-screw h^1 carried by the bracket g^2 .

- The paper feed roller H is connected with a spur-wheel h^2 meshing with a corresponding wheel e of the same size on the feed shaft E so that the shaft of the roller H is driven at the same speed as that of the feed shaft, which latter carries a paper feed roller I 10 of the same diameter as the roller H and like it preferably made of a relatively soft material such as rubber. The paper passes between the feed rollers H and I and then over a guide i which directs the paper across the plane of the inking ribbon and prevents it from sagging or dropping down below the feed rollers before passing across the type. The paper feed roller I is also the impression roller or platen of the machine. 15
- On the feed shaft E is mounted a ratchet-wheel J and a detent-wheel K, both of which revolve with the roller I. The detent-wheel K is preferably of slightly larger diameter than the ratchet-wheel and is engaged by a 20 roller-dog k carried by a spring arm k^1 attached to a bracket K^1 rising from the bed plate. This bracket is provided with devices k^2 at its base by means of which it may be adjusted to regulate the position of the 25 dog k relatively to the detent-wheel and this position and also the pressure exerted by the dog on the wheel K may be regulated by the set-screw K^2 . The detent is for the purpose of preventing an overthrow of the 30 ratchet-wheel and for also preventing a return movement of the feed shaft. 35

The ratchet-wheel J is engaged by a pawl L carried by the feed plate M and this pawl comprises a shank l pivoted at its lower end 40 to a bracket m on the rear part of the feed plate and engaged by a spring l^1 which holds the pawl in yielding engagement with the ratchet-wheel and out of engagement therewith when desired and when the pawl is 45 thrown over to the left. The upper end of the shank l is formed with a socket l^2 to receive the tooth l^3 which is preferably of the shape shown (Fig. 6) and which is preferably made of relatively soft material in 50 order that the noise usually incident to the operation of machines of this class may be reduced to a minimum.

I preferably make the tooth of rubber of a kind which may be described as somewhat 55 harder than soft rubber and somewhat softer than ordinary hard rubber being so soft that noise is practically eliminated and yet hard or stiff enough to properly actuate the ratchet-wheel and to withstand ordinary 60 wear for a considerable time. The socket l^2 is so shaped that the tooth l^3 may be easily inserted or withdrawn, and yet held in place while operating. The upper or inner end of the tooth presses against the under side 65 of the curved upper portion of the pawl-

shank while the sides of the tooth are firmly gripped by the sides of the socket. The tooth may be easily withdrawn when necessary and replaced by a new one.

The feed plate M is preferably of the 70 form shown in plan in Fig. 1. It is preferably made of sheet metal flanged at its edges to stiffen it and is also formed with a middle concavo-convex portion m^1 for a similar purpose. On opposite sides of its middle 75 portion it is formed with arms or ears m^2 which rest on posts m^3 carrying pins m^4 which extend through perforations in the ears. These posts constitute the fulcrums on which the feed plate rocks. 80

The front part of the feed plate is formed with two forwardly-extending diverging arms m^5 to which are attached plates m^6 of hard rubber or other suitable material to receive the fingers of the operator when actuating the feed plate independently of any movement of the keys. At its rear end the feed plate is formed with a V-shaped part M^2 which is so stamped as to provide a V-shaped rib x on its under side which is preferably covered with felt or other soft material x^1 to deaden the noise when the keys are operated. 85

The rear end of the feed plate is held normally depressed by a spring N connected at 95 its lower end with the bed plate and connected at its upper end with the feed plate by a screw n provided with an adjusting nut n^1 . This connection of the spring N with the feed plate is slightly in rear of the 100 vertical plane of the points m^4 as indicated by the line n^x in Fig. 1 so that the feed plate is given only a slight movement and is easily operated. The spring N is not directly connected with the bed plate but with a bearing 105 plate O which is in turn rigidly connected with the bed plate. This plate O also carries the posts m^3 and its rear end is perforated to receive a screw P, the upper end of which is firmly attached to the feed plate 110 and the lower end of which, below the plate O, carries a buffer p of some soft material, the position of which may be regulated by the adjusting nuts p^1 . The buffer p, which is adapted to strike against the under side 115 of the plate O, tends to limit the upward movement of the rear end of the feed plate and this movement may also be limited by buffers or cushions P^2 attached to the bed plate below the arms m^5 of the feed plate. 120

I find in practice that the buffer p may be omitted, but it is preferably placed on the machine to provide for any unequal expansion or contraction of the sheet metal of which the feed plate is made. Furthermore, by employing an adjustment buffer the throw of the feed plate may be conveniently regulated. 125

The bearing plate O preferably consists of a rectangular frame comprising front and 13

rear bars o , o^1 , side bars o^2 , o^3 , and a middle bar o^4 , extending parallel with the side bars and arranged mid-way between them. This bearing plate is rigidly attached to the bed plate and the bars o^2 , o^3 , o^4 are formed with V-shaped grooves v to receive the knife-edged bearing bars of the key levers R.

The general arrangement of the key levers is clearly shown in Fig. 10, each carrying 10 at its front end a finger-piece r^1 and each provided at its rear end with a type r^2 . There are preferably five levers R on each side of the central longitudinal axis of the machine. One set of levers preferably carries type to mark dots while the other set carries type to mark dashes and the rear ends of the levers are so formed as to carry the type in a straight line one behind the other slightly to one side of the central 15 longitudinal axis of the machine. The face or upper ends of the type are all normally held in the same horizontal plane and the distance between the two rows of types is considerably less than the distance between 20 the teeth in the ratchet-wheel for the purpose described in my patents above mentioned.

Each key lever is firmly connected with a bearing bar S arranged beneath it and a 30 short distance above the top of which it is held by a spacing block s so that each key lever may extend across the bearing bars of other levers without coming in contact with them (Fig. 12). Each bearing bar projects 35 from opposite sides of the lever to which it is connected and at its opposite end it is formed with downwardly-projecting flanges s^1 having knife edges q at their lower ends adapted to enter the grooves v in the bearing plate O. The bar S also has a downwardly extending flange s^2 in line with the flanges s^1 . The knife edges q of the bearing bar S of each key lever on each side of the machine is received in a groove v in the 40 middle bar o^4 of the bearing plate O and in a corresponding groove in one of the side bars o^2 , o^3 . These grooves are in accurate alignment with each other for all the bearing bars and the key levers rock on these 45 knife edges on the lines z in Fig. 10. End-wise movement of the bearing bars is prevented by plates T attached to the bearing plate O at the ends of the bars S, as clearly shown in Fig. 10 and also in Fig. 11. The 50 downward movement of the rear ends of the key levers is limited by a stop-block R^2 provided with a cushion r^5 and the rear ends of the type bars normally rest on this stop-block R^2 .

55 By reference to Fig. 10 it will be observed that the type on each key lever is arranged the same distance from the line on which the lever rocks as the type on every other lever. It will also be observed that the points W 60 of the key levers which come in contact with

the rib α on the feed plate M are equidistant from the lines z on which the respective key levers rock so that the feed plate is moved to the same extent when any key lever is actuated.

70

Each key lever is held in its bearings by a spring B^2 , which is attached to the flange s^2 of the bearing bar S mid-way between the ends of said bar and this point of adjustment is in line with the knife edges q on 75 which the key lever rocks. The lower end of each spring B^2 is attached to a bracket B^3 secured to the bearing plate O. By this arrangement each key is held in its bearing. Should it jump partially out of these bearings it is immediately returned thereto and in the normal operation of the keys there is practically no force exerted which interferes with the easy movement of the key.

80

The general operation of the machine is 85 similar to that of all machines of this class. It will be understood that the inking ribbon is wound from one spool to another, over the type, and beneath the impression roller, and that the strip or ribbon of paper 90 is fed beneath the impression roller above the inking ribbon. When the ribbon is wound off from one spool on to the other the lever D may be thrown over to the 95 opposite side so as to cause the empty spool to wind the ribbon from the other spool. Each time that a key lever is depressed it not only causes an impression to be made on the paper but it also raises the feed plate, thus causing the pawl L to engage a new 100 tooth in the ratchet-wheel and when the key thus actuated is released the feed plate drops at its rear end, pulling down the pawl and causing the feed shaft to be turned the space of one tooth to thus actuate the ribbon-feed mechanism and also the paper-feed mechanism.

105

110 My machine is so constructed, as more fully described in my former patents, that keys on opposite sides of the machine may be actuated simultaneously so as to simultaneously print dots and dashes. The mechanism is so constructed, and arranged, as hereinbefore described, that the parts are operated with great delicacy of touch, with 115 uniform leverage and with no objectionable noise. By providing each key lever with a bearing bar having the bearing points located at a considerable distance apart all side-wise movement of the levers is prevented and perfect alignment of the type is 120 insured.

120

125 In my application for Patent No. 497,190 filed May 20, 1909, I have claimed the novel features of the key levers and their bearings herein shown and described.

I claim as my invention:

1. In a stenographic machine the combination of a series of finger keys each carrying a type, a platen, a feed shaft connected 130

- therewith, a feed plate actuated by the finger keys, a ratchet wheel carried by the feed shaft, and a pawl carried by the feed plate provided with a tooth of relatively soft non-metallic material engaging the ratchet wheel.
2. In a stenographic machine, the combination of a feed shaft, a ratchet-wheel carried thereby, a pawl provided with a tooth of relatively soft non-metallic material engaging the ratchet-wheel, means for actuating the pawl, a detent wheel connected to revolve with the ratchet-wheel, and a detent dog of relatively soft non-metallic material engaging the detent wheel.
3. In a stenographic machine, the combination of a feed shaft, a ratchet-wheel carried thereby, a pawl provided with a tooth of relatively soft non-metallic material engaging the ratchet-wheel, means for actuating the pawl, a detent wheel carried by the feed shaft, a detent dog of relatively soft non-metallic material engaging the detent wheel, and means for adjusting the position of the dog relatively to the detent wheel.
4. In a stenographic machine, the combination of a feed shaft, a ratchet-wheel carried thereby, a pawl comprising a tooth of relatively soft non-metallic material, and a shank provided with a socket into which the dog is removably fitted, and means for actuating said pawl.
5. In a stenographic machine, the combination of the base plate, the feed plate, posts on which the feed plate rocks, a spring connected with the feed plate in rear of the plane of the posts for depressing the rear end of the feed plate, and an adjustable buffer for limiting the upward movement of the rear end of the feed plate.
6. In a stenographic machine, the combination of the base plate, the bearing plate rigidly attached thereto, the feed plate, posts mounted on the bearing plate on which the feed plate rocks, a spring connected with the bearing plate and with the feed plate in rear of the posts and which normally de-

presses the rear end of the feed plate, and a buffer suspended from the rear portion of the feed plate and adapted to engage the bearing plate.

7. In a stenographic machine the combination of the platen, a set of finger keys on one side of the machine carrying type at their rear ends arranged in line parallel with the axis of the platen and some of which keys extend diagonally forward from the printing point, a similar set of keys on the opposite side of the machine similarly arranged, and a feed plate carrying a pawl for operating the platen having a part against which the keys strike which, at its middle portion is nearer to the front of the machine than the side portions thereof, which latter extend rearward and diagonally outward over the striking parts of the keys.

8. In a stenographic machine the combination of the rotary platen, a set of finger keys on one side of the machine carrying type arranged in line with the axis of the platen, and some of which keys extend diagonally forward and outward from the printing point, a similar set of keys on the opposite side of the machine similarly arranged, a feed plate carrying a pawl for operating the platen and having a part, against which the keys strike, which at its middle portion is nearer the front of the machine than the side portions, which latter extend rearward and diagonally outward over the striking portions of the keys, each of which striking portions is located the same distance from the pivotal point of the key which strikes it as the point of engagement of each of the other keys with the feed plate is located from its pivotal point.

In testimony whereof, I have hereunto subscribed my name.

WILLIAM J. KEHOE.
